UNITED STATES PATENT OFFICE

2,580,103

COMBINED SHELF AND WALL PROTECTOR

Nellie G. Keller and William J. Keller,
St. Louis, Mo.

Application December 26, 1945, Serial No. 637,273

1 Claim. (Cl. 45—36)

1

This invention relates to a combined shelf and wall protector.

The object of the present invention is the provision of a device adapted to be removably secured to a kitchen wall to serve as a hollow shelf above and to the back of a kitchen range, and which is provided with a roller curtain, or wall protector which, when pulled down, will serve as a wall protector to prevent smoke, grease and dirt accumulation on the wall adjacent the top of the range.

A further object of the invention is to provide a device of the character of such construction that the wall protector may be completely concealed by the shelf when not in use.

A further object of the invention is the provision of a novel kitchen device which will be ornamental, as well as useful, simple and inexpensive in cost of manufacture, and highly efficient for the purpose intended.

These and other objects we attain by the construction, arrangement and combination of parts shown in the accompanying drawings, wherein for the purpose of illustration, is shown a preferred embodiment of the invention.

Referring to the accompanying drawings forming a part of this specification, wherein like characters of reference denote similar parts throughout the several views:

Fig. 1 is a view, in perspective, of a kitchen range and a combination kitchen shelf and wall protector arranged in association therewith, the latter embodying the features of our invention.

Fig. 2 is a front elevation of the device embodying the features of the invention, the same being shown as partly broken away.

Fig. 3 is a sectional elevation taken on line 3—3 in Fig. 2.

Fig. 4 is an end view looking at the right hand end of the shelf.

Fig. 5 is an end view looking at the left hand end of the shelf.

The present invention is concerned with a device for keeping the kitchen wall clean and free from smoke, grease and dirt accumulation adjacent the top of a kitchen range, and when not in use serving as a shelf adjacent the top of the range.

Briefly, the device consists of a hollow shelf and a suitable flexible and washable roller curtain wholly contained within the shelf and out of view when not in use, and exposed to view below the shelf to cover the wall surface above and to the rear of a kitchen range when in operative position.

2

The shelf designated, generally as A, consists of an elongated back wall 1, end walls 2 and 3, a top wall 4 and a movable front wall 5, which when assembled as shown, constitutes a hollow shelf.

5 The back wall 1 is provided with a plurality of openings 6, or equivalent means, for removably hanging the device from suitable fastening devices 7, which are secured to the kitchen wall 8 for supporting the shelf in position a suitable distance above and to the rear of a kitchen range 9.

The front edge of the top wall 4 is upturned to provide a flange 10 so that the top of the shelf can serve as a plate or other dish rail.

15 The movable front wall 5 is preferably curved in shape and fits between the end walls 2 and 3. The wall 5 is preferably hinged at its upper end by means of a suitable hinge pin 11 supported in openings 12 in the end walls 2 and 3. The lower 20 edge of the front wall 5 is upturned, as at 13 to provide a flange which, when the front wall is in its closed position, contacts the inner face of the back wall 1. Inwardly projections, or protuberances formed by indenting, or depressing 25 the material of the end walls outwardly, as at 14 adjacent their rear lower corners, serve to provide means to hold the front wall closed after the side edges of the front wall have passed by the protuberances 14.

30 A roller 15, spring controlled, such for instance as a window shade roller, is supported at its ends by the end walls 2 and 3 which serve as roller supporting brackets. The walls 2 and 3 are resiliently flexible so that the roller can be detachably supported. The end wall 2 is provided adjacent its upper rear corner with an opening 16 to receive the cylindrical fitting 17 at one end of the roller, and the other end wall 3 is provided adjacent its upper rear corner with a slotted opening 18 to receive the rectangular fitting 19 at the opposite end of the spring controlled roller.

35 The suitable curtain, or shade like material E of plastic, or other suitable material, transparent or figured and preferably washable, is suitably secured at its one end to the roller 15 and its other, or free edge is provided with a loop 20 to receive a reinforcing strip 21. The curtain, or shade like material serves as a wall protector, as is obvious, and it is preferably as wide, or wider than the width of the kitchen range, so as to protect the surface area adjacent the top 50 of the range between the shelf and the range.

From the foregoing description, it is clearly apparent that when the wall protector curtain is

not in use that it is rolled up on the roller and concealed from view within the hollow shelf. The hinged front wall 5 can be easily lifted to remove, or replace the roller 15 and the shade thereon, and the wall 5 usually stands slightly open as in the dotted line position when the wall protector curtain is drawn downwardly to serve as a protection for the wall adjacent the top of the range during cooking periods.

It will be obvious that the construction hereinbefore set forth is capable of change and modification without materially departing from the spirit of the invention, and we accordingly do not wish to limit ourselves to such specific structure, except as hereinafter claimed.

What we claim is:

In a wall protector for kitchens to protect the wall from grease and the like when cooking foods on a range, the combination of a right angular member constituting a back wall and a top wall projecting forwardly from the upper edge thereof, the back wall having slotted openings adjacent the upper corners thereof adapted to receive wall fasteners for detachably supporting the member to the rear of and above the top of the range, end walls connected with the back and top walls and having convexed front edges, a concaved-convexed front wall disposed between the end walls and below the top wall, a hinge pin carried by the end walls adjacent the upper front corners thereof from which the front wall is hingedly suspended, detents projecting inwardly from the end walls for holding the front wall

in its closed position, the lower edges of the front wall terminating in an inwardly projecting flange adapted to engage the back wall when in its closed position, and said back, top, end and front walls providing a compartment adapted to contain a roller supported curtain which may be pulled down when the side edges of the front wall have been moved forwardly past the detents to provide a gap between the flanged lower end of the hinged front wall and the back wall and to conceal the curtain when raised and the hinged front wall is in its closed position.
